(57) **CLAIM**

The ornamental design for an apparatus for capturing an image of the eye, as shown and described.

DESCRIPTION

FIG. 1 is a top perspective view of an apparatus for capturing an image of the eye with an angled top attachment;

FIG. 2 is a front view of the apparatus for capturing an image of the eye shown in FIG. 1;

FIG. 3 is a side view thereof;

FIG. 4 is a top view thereof; and,

FIG. 5 is a bottom view thereof.

In the drawings, the broken lines are for the purpose of illustrating environment only and form no part of the claimed design.

1 Claim, 4 Drawing Sheets
